FIG 2

FIG. 2

FIG. 1 is a perspective view of a child's slide which illustrates the right front of the slide when it is in its upstanding position;

FIG. 2 is a front elevation of the slide in its upstanding position;

FIG. 3 is a perspective view of the slide when it is inverted and placed on a substantially horizontal surface such that a ball will remain within the serpentine channel as the ball rolls down the slide from the rear to the front thereof;

FIG. 4 is a side elevation of the slide in its upstanding position;

FIG. 5 is a perspective view of the slide which illustrates the right rear of the slide when it is in its upstanding position;

FIG. 6 is a rear elevation of the slide in its upstanding position;

FIG. 7 is a longitudinal sectional view looking into the plane represented by line VII-VII of FIG. 6; and

FIG. 8 is a side elevation of the slide in the inverted, ball-rolling position shown in FIG. 3.

I claim:

The ornamental design for a child's slide, substantially as shown and described.
